UNITED STATES PATENT OFFICE.

FRED HARRIS LYNDS, OF WOONSOCKET, RHODE ISLAND, ASSIGNOR TO ELECTRIC
COMPOSITOR COMPANY, OF NEW YORK, N. Y., A CORPORATION OF NEW JERSEY.

LINOTYPE-MOLD.

1,078,930.

Specification of Letters Patent. Patented Nov. 18, 1913.

Application filed January 18, 1911. Serial No. 603,209.

To all whom it may concern:

Be it known that I, FRED HARRIS LYNDS, a citizen of the United States, residing at Woonsocket, in the county of Providence 5 and State of Rhode Island, have invented a certain new and useful Improvement in Linotype-Molds, of which the following is a full, clear, and exact description.

This invention is an improvement on linotype 10 molds adapted for the casting of cored-out or hollow linotypes.

The invention may be employed as an improvement on the linotype mold which forms the subject matter of the Petri-Pal- 15 medo Patent No. 1,005,463, granted October 10, 1911, and is so shown in the drawing.

The object of the invention is to enable the linotype to be pushed out of the mold and stripped from the core or cores more easily 20 and quickly and with less liability to injuring the slug than is possible with the linotype molds of said prior application.

The invention consists in the employment of hollow cores having thin walls instead of 25 the solid cores shown in said prior application.

In the drawing, Figure 1 is a rear view of a linotype mold in which this invention is embodied. Fig. 2 is a central sectional view 30 taken in the plane of line 2—2 on Fig. 1, except that one of the cores is sectioned. Fig. 3 is a perspective view of three detached cores showing one of them in section in a plane at right angles to the section shown in 35 Fig. 2.

Referring to the parts by letters, A represents the mold which is, as is customary, a built-up structure having a mold slot *a* extending through it from front to back.

40 B represents a core which has a tail piece *b* adapted to fit and to be secured in a recess *a'* in the rear face of the mold. The rear face of the core and its tail piece, when the core is secured in place as stated, are in the

same plane with the rear face of the mold. 45 The length of the core is not material, although preferably it should be of such length that several cores may be used in the mold slot. The thickness of the core should be less than the width of the linotype slot; 50 and the height of the core is such that its front end does not extend to the front face of the mold by about a quarter of an inch more or less. These cores are hollow and have thin walls; and therein lies the difference 55 between them and those cores which are shown and described in the prior patent referred to.

Experience with molds equipped with solid cores and others equipped with hollow 60 thin-walled cores shows conclusively that the linotypes may be pushed out of the mold slots containing the hollow cores and stripped from such cores more easily and quickly and with less liability of injuring 65 the linotype than is possible when the solid cores are employed. The thinness of the walls of these cores makes them somewhat flexible and yielding under the pressure due to the contraction of the linotype. It is 70 probable that this is the reason why linotypes cast in molds which are provided with hollow cores, as shown and described, may be removed from the mold slot and stripped 75 from the cores without danger of injuring the linotype.

Having described my invention, I claim:

The combination of a linotype mold having a mold slot through it from front to rear, combined with a hollow core immovably held within said mold slot, said core having thin flexible imperforate walls. 80

In testimony whereof, I hereunto affix my signature in the presence of two witnesses.

FRED HARRIS LYNDS.
